ABSTRACT

A circuit for supplying the final anode voltage to a CRT from a horizontal output transformer has a voltage tripler circuit. A circuit comprising a diode coupled in series with the parallel combination of a resistor and capacitor is coupled across the transformer. This prevents ringing during the scanning time, and hence, improves the regulation of the output voltage.

EHT SUPPLY PARTICULARLY FOR TELEVISION RECEIVERS

This is a continuation of application, Ser. No. 857,674, filed Sept. 15, 1969 now abandoned.

The invention relates to a circuit arrangement for EHT supply to the final anode of a picture display tube in a picture display device which is provided with a line output stage transformer, an EHT winding on the core of this transformer, a multiplier circuit formed by capacitors and unidirectional components which circuit is connected to the terminals of the EHT-winding in order to multiply the voltage peaks occurring across this winding and to rectify the multi-plied voltage.

Such a method of generating the EHT has been known for a long time. It is, for example, described in the book *Television* by F. Kerkhof and W. Werner, (1954) in the FIGS. 7.3-2 (page 196) and 7.3-8 (page 204). The output power in the colour picture display tube is large, namely in the order of 40 Watts. The EHT regulation must be good since otherwise the colour purity at large beam currents would deteriorate due to the decrease of the EHT. The greater the internal resistance of the EHT generator, the greater the decrease of the EHT as the beam current increases. Particularly in case of large powers this internal resistance will then have to be small for a good regulation. In addition, the EHT will be smaller when the internal resistance of the EHT-source is large and therefore the light output is not as large as in the case of a small internal resistance. Also, due to a large internal resistance the picture displayed may "breathe" as a result of variations in the taken beam current, that is to say the dimensions of the picture may vary. In fact, the EHT decreases when beam current increase. The internal resistance can slightly be reduced by using a multiplier circuit. It has, however, been found that the internal resistance thus obtained is larger at low beam currents than at high beam currents.

It is evident that this problem can be solved by connecting a resistor across the terminals of the EHT source, so that a current of at least 200 μ A is always drawn from the multiplier circuit while ringing pulses, occurring in the EHT and the cause of which will further be explained, are also clipped off. Since the EHT required for the final anode in colour picture display tubes is, however, 25 kV, this would require an expensive chain of a large number of well insulated resistors. A better solution would be a voltage dependent resistor instead of the said chain, but such an element is bulky. It is alternatively possible to use a so-called ballast tube, but the drawback of the needless loss of power remains, while such a tube is not free from X-ray radiation which necessitates a screen. An object of the invention is to solve the mentioned problem in a simple manner without it being necessary to derive an additional drain and to this end, the circuit arrangement is characterized in that a load circuit consisting of at least one diode in series with the parallel arrangement of a resistor and a capacitor is connected between the terminals of the EHT winding and that the diode is given a direction of conduction such that ringing pulses occurring at the said winding and having a polarity opposite to that of the pulses occurring during the line flyback are clipped off.

It is to be noted that it has become common practice to tune line output transformers to frequencies one of

which is the flyback frequency and the other is substantially an odd harmonic thereof. Such a tuning is described in the U.S. Pat. No. 2,805,384 and in the U.S. Pat. No. 3,500,116. Due to the tuning to the so-called fifth harmonic already a small internal resistance of the EHT source is obtained, because the peaks of the EHT pulses to be rectified have become flatter. As a result the picture "breathes" less when the taken beam current varies. However, since the said manner of tuning is never entirely ideal, oscillations may still occur right at the beginning of the line scan period.

In order that the invention may be readily carried into effect, a few embodiments thereof will now be described in detail, by way of example, with reference to the accompanying diagrammatic drawing, in which:

FIG. 1 shows a multiplier circuit of a known type, i.e. a tripler,

FIG. 2 shows the waveform of the input voltage of the circuit arrangement of FIG. 1,

and FIG. 3 shows an embodiment of the circuit arrangement according to the invention.

FIG. 1, terminal A is connected to the EHT winding, whose other end is connected to earth, of the line output transformer across which the peak-to-peak amplitude of the voltage of the positive pulse occurring during the line flyback period has a value of, for example, 8.4 kV. The series arrangement of a diode D_1 and a capacitor C_1 is connected between terminal A and earth, the anode of diode D_1 being connected to terminal A. During the line flyback periods capacitor C_1 is charged to the maximum value of the voltage which is present at terminal A. During the line scan periods capacitor C_2 is charged through diode D_2 by the positive potential of capacitor C_1 because terminal A is then approximately at earth potential. When the line flyback pulses occur voltage pulses are applied in the capacitor C_2 to diode D_3 , but they are superimposed on the direct voltage potential present across the terminals of this capacitor. As

30 a result capacitor C_3 is charged to twice the value of the input pulse at terminal A. The same manner capacitor C_4 is charged through diode D_4 during the line scan periods up to the direct voltage potential across capacitor C_3 , while voltage pulses are applied through D_5 to the stray capacitance C_5 of the picture display tube during the flyback periods, the potential across C_5 being increased by the d.c. potential across capacitor C_4 . These pulses are rectified by diode D_5 and capacitor C_5 is charged to a potential, i.e. the EHT potential, which is 40 equal to substantially three times the amplitude of the voltage pulse at the input of the circuit. FIG. 2 shows the waveform present at the terminal A during the scanning and flyback periods, the aforementioned ringing pulses being shown at the beginning of the scan periods.

During the line flyback period diodes D_1 , D_3 and D_5 conduct during time t_1 (FIG. 2), while diodes D_2 and D_4 conduct during the scanning period which starts at the instant t_2 . The ratio between the periods of conduction of the said diodes depends on the EHT power being taken by the display tube. If the beam current is low, the diodes rectify the full amplitudes between points a and b of the waveform of FIG. 2. If the beam current exceeds the value of approximately 200 μ A the ringing pulses shown in FIG. 2 after the instant t_2 are clipped off, but as a result thereof the EHT decreases by at least 2 kV. Once these ringing pulses have been clipped off,

the EHT only decreases slightly with a further increase of the beam current.

FIG. 3 shows an embodiment of the circuit arrangement according to the invention in which elements corresponding to those of FIG. 1 have the same reference numerals. Between terminal A, which is the voltage-conveying end of the EHT winding of a line output transformer not shown in the Figure, and ground there is provided the series arrangement of a resistor R_1 and a diode D_6 in such a manner that the anode of diode D_6 is connected to ground. Resistor R_1 is shunted by a capacitor C_6 and diode D_6 is shunted by the series arrangement of a resistor R_2 and a capacitor C_7 .

When the ringing oscillation of the voltage at terminal A has a negative going portion, diode D_6 conducts resulting in a current flowing through the parallel arrangement of capacitor C_6 and resistor R_1 so that the negative ringing oscillations voltage is clipped off and cannot therefore contribute to the EHT which is developed across capacitor C_5 . As a result the generated EHT will have substantially the same value at a small and a large beam current.

Due to capacitor C_6 there is produced a positive voltage at the cathode of diode D_6 which voltage is further smoothed by the series arrangement of R_2 and capacitor C_7 . The first acceleration anode of a colour picture display tube of the shadow mask type requires a voltage in the order of 700 to 800 V. This voltage may advantageously be supplied by the direct voltage across capacitor C_7 . For line output stages which include semiconductors, it is common practice to use a separate peak rectifier so as to obtain this voltage, and due to the step mentioned above, this separate rectifier may be omitted.

The focussing electrode of a colour picture display tube of the shadow mask type requires a potential which is approximately 5 kV and which can be derived either by means of a potential divider between the EHT and ground, or from a tap on the line output transformer. This voltage can now be derived by means of a potentiometer V_R connected in parallel with capacitor C_1 of the multiplier circuit. The small current which flows through this potentiometer, also contributes to smoothing the peak of the line flyback pulse of FIG. 2, which causes a further reduction of the internal resistance of the EHT source.

Due to the choice of the ratio between the capacitances of capacitors C_6 and C_2 a certain extent of protection against a possible flashover in the picture display tube can be obtained for the circuit being shown to the left-hand side of point A in FIG. 3. When such flashover occurs, the EHT line, *i.e.* capacitors C_5 , is short-circuited to ground. As a result thereof the charge of capacitors C_1 , C_3 and C_4 flows away through diodes D_2 , D_4 and D_5 . However, since diode D_1 is blocked, the charge of capacitor C_2 cannot find a path other than the EHT winding through terminal A. The voltage across capacitor C_1 is substantially zero, so that a negatively directed current pulse arises at the input of the tripler circuit. A measured value thereof was approximately 10 A, which may result in damage of the line output transistor. If, however, the voltage across capacitor C_2 becomes more negative than the voltage across capacitor C_6 , diode D_6 conducts and the series arrangement of capacitors C_2 and C_4 forms capacitor C_6 a capacitive potential divider so that only a small part of the voltage cause by the flashover is conveyed

to terminal A when the capacitance of capacitor C_6 has been rendered much larger than that of capacitor C_2 . The line output transistor is somewhat protected in this manner.

5 A further step may be to include a resistor R_3 between capacitor C_1 and ground, so that the discharge current flowing through this capacitor is reduced. For resistor R_3 a value is chosen, for example, 470 Ω which is much larger than that of the discharge path through 10 the display tube, which is approximately 50 Ω . When a breakdown occurs, a negative voltage is produced across resistor R_3 so that diode D_1 becomes conducting. Capacitor C_6 can therefore be discharged which results in a still better protection of the line output transistor.

15 The following components were used in one embodiment of the circuit arrangement according to the invention:

Capacitors C_1 , C_2 , C_3 and C_4 } tripler LP 1174
Diodes D_1 , D_2 , D_3 , D_4 and D_5 } (Mullard Ltd)

Capacitor C_6 : 10nF.

Capacitor C_7 : 1nF

Diode D_6 : Mullard type BY 140.

Resistor R_1 : 500 k Ω .

Resistor R_2 : 10 M Ω .

What is claimed is:

1. A circuit for supplying ulti electrode voltage to a display tube from a horizontal output transformer output winding comprising means having an input coupled to said output winding and an output coupled to said electrode for multiplying and rectifying the winding flyback pulses; and means coupled to said output winding for eliminating ringing pulses occurring at said output winding and having a polarity opposite to that of said flyback pulses, said eliminating means comprising a diode, a resistor, and a capacitor coupled in parallel with said resistor, said resistor and capacitor being coupled in series with said diode, whereby a junction is formed and the ulti voltage is substantially a constant regardless of the ulti current.

2. A circuit as claimed in claim 1 further comprising means for obtaining an anode supply voltage from said junction.

3. A circuit as claimed in claim 2 wherein said obtaining means comprises a second resistor coupled to said junction, and a second capacitor coupled to said second resistor.

4. A circuit as claimed in claim 1 wherein said multiplying and rectifying means comprises a plurality of diodes and capacitors arranged in a voltage multiplier configuration, one of said capacitors being coupled to said eliminating means capacitor, another one of said capacitors and one of said diodes being coupled in series and to said winding.

5. A circuit as claimed in claim 4 wherein the capacitance of said eliminating means capacitor is substantially larger than the capacitance of said capacitor coupled thereto.

6. A circuit as claimed in claim 4 further comprising a resistor coupled in series with said diode and capacitor that are coupled to said winding.

7. A circuit as claimed in claim 1 wherein said display tube comprises a color picture tube.

8. A circuit as claimed in claim 1 wherein said multiplying and rectifying means multiplies said winding voltage approximately by a factor of three.

9. A circuit for supplying ulti electrode voltage to a display tube from a horizontal output transformer

output ulti^r tap comprising means having an input coupled to said output and an output coupled to said electrode for multiplying and rectifying the winding flyback pulses; and means coupled to said output ulti^r tap for eliminating ringing pulses occurring at said output ulti^r 5

tap and having a polarity opposite to that of said flyback pulses; whereby the ulti^r voltage is substantially a constant regardless of the ulti^r current.
